REMOVAL OF SULFUR COMPOUNDS FROM HYDROCARBONS WITH α -SODIUM-SODIUM ACETATE

Guenther Nottes and Emil Weiss, Ludwigshafen (Rhine), Germany, assignors to Badische Anilin- & Soda-Fabrik Aktiengesellschaft, Ludwigshafen (Rhine), Germany

No Drawing. Filed Apr. 29, 1959, Ser. No. 809,615

Claims priority, application Germany May 9, 1958

7 Claims. (Cl. 208—232)

This invention relates to the refining of hydrocarbons. The presence of sulfur compounds in hydrocarbons, such as gasolines, diesel oils, fuel oils, lubricating oils and the like, is very undesirable.

The use of free alkali metals, such as sodium and potassium, is known, *inter alia*, as a method for the removal of sulfur compounds from hydrocarbons. A great disadvantage in the use of free alkali metals lies in the fact, however, that these metals are readily oxidizable and also very sensitive to traces of moisture and carbon dioxide in the air.

We have now found in accordance with the invention that sulfur compounds, especially, mercaptans, can be extensively removed from liquid hydrocarbons, such as gasolines, diesel oils, jet fuels, distillate fuel oils, fractions of the distillation of coal tar and lubricating oils, by treating the hydrocarbon with alpha-sodium-sodium acetate ($\text{NaCH}_2\text{COONa}$). The compound, alpha-sodium-sodium acetate can be prepared by the process disclosed in U.S. Patent No. 2,850,528, granted September 2, 1958.

The amount of alpha-sodium-sodium acetate to be used in this process depends on the content of sulfur compounds in the crude.

In general, even very small amounts of alpha-sodium-sodium acetate, for example 0.01 to 5% by weight, advantageously 0.1 to 2% by weight, are sufficient to achieve good refining action.

The action of alpha-sodium-sodium acetate on the raw material to be refined may take place at room or at elevated temperature, e.g. up to about 350° C., preferably not higher than 250° C. Generally it is desirable that no cracking of the hydrocarbon should take place.

The pressure employed can be normal pressure up to any high pressures required in order to keep the hydrocarbon or hydrocarbon mixtures liquid at the working temperature.

The refining may for example be carried out by stirring pulverulent alpha-sodium-sodium acetate into the hydrocarbon to be refined, to form an intimate mixture or slurry. Thus the alpha-sodium-sodium acetate will react with the sulfur compounds forming a sludge. The purified hydrocarbon can be easily separated in a conventional manner, most favorably by distillation, filtration or centrifuging.

A specially advantageous embodiment comprises the activation of the alpha-sodium-sodium acetate by the addition of a small amount of monohydric, dihydric or polyhydric alkyl, aryl, aralkyl or cyclic alcohols, e.g. methanol, isobutanol, dodecyl alcohol, glycol, glycerol, benzyl alcohol, cyclohexanol, hexylene glycol. The alcohol is added in an amount of about equal to the alpha-sodium-sodium acetate, that is e.g. from 0.01 to 5% by weight.

The following examples will further illustrate this in-

vention but the invention is not restricted to these examples. The parts and percentages are by weight.

Example 1

5 6 parts of $\text{NaCH}_2\text{COONa}$ are stirred into 200 parts of a doctor-positive distillate fuel oil of yellowish-green appearance (10 ccs. correspond to 0.005 cc. of AgNO_3) according to the mercaptan determination method in C. Zerbe, "Mineralöle und verwandte Produkte" (Mineral Oils and Allied Products), page 536, with a sulfur content of 0.86%. After 5 minutes, 10 parts of isobutanol are added and the whole stirred for another 5 minutes. The isobutyl alcohol is then distilled off and recovered.

10 The distillate fuel oil is then distilled off in *vacuo* (18 mm. Hg), 195 parts of raffinate being obtained. Solid grey crusts remain in the still.

15 The oil treated according to this invention is water-clear, almost odorless and shows a negative doctor test. The sulfur content has diminished to 0.27%.

20 In a blank test without addition of $\text{NaCH}_2\text{COONa}$, no change in the properties of the distillate fuel oil is achieved by a corresponding identical vacuum distillation.

Example 2

25 A mixture boiling in the gas oil range and consisting of a recycle oil from a catalytic cracking plant with a straight-run diesel oil (ratio 6:4) and which deposits a sediment when allowed to stand for a long period, is treated with 1% of $\text{NaCH}_2\text{COONa}$ according to Example 1 employing 5 parts of a technical mixture of amyl alcohols.

30 A waterclear product is obtained which has a color number of 0.18 in the Saybold colorimeter and a Conradson test of 0.012%. The untreated oil had a color number of 1 and a Conradson test of 0.056%.

35 The sulfur content is reduced by the treatment according to the invention from 0.57% to 0.24%.

Example 3

40 A pale green colored crude gasoline from a catalytic cracking plant and having a sulfur content of 0.11% showed an ASTM glass dish gum test of 8 mg./100 ccs. 100 parts of this gasoline are stirred with 1% of $\text{NaCH}_2\text{COONa}$ in an autoclave under a pressure of 3 excess atmospheres for 30 minutes at 100° C. From the resulting reaction mixture, the gasoline is distilled off. 96 parts of a refined product are obtained which shows an ASTM gum test of 1.6 mg./100 ccs. and a sulfur content of 0.03%. The product was waterclear.

45 We claim:

1. A process for the removal of sulfur-containing impurities from a crude liquid hydrocarbon which comprises treating the hydrocarbon with alpha-sodium-sodium acetate ($\text{NaCH}_2\text{COONa}$).

50 2. A process as claimed in claim 1 which comprises treating the hydrocarbon with alpha-sodium-sodium acetate in the presence of an alcohol as an activator.

3. A process as claimed in claim 1 which comprises treating the hydrocarbon with alpha-sodium-sodium acetate in an amount of 0.01 to 5% by weight.

55 4. A process as claimed in claim 3 which comprises treating the hydrocarbon with the alpha-sodium-sodium acetate in the presence of an alcohol in the amount of 0.01 to 5% by weight as an activator.

5. A process for the removal of sulphur-containing impurities from a crude liquid hydrocarbon which comprises contacting the crude hydrocarbon with from 0.01 to 5% by weight of alpha-sodium-sodium acetate for reaction with sulphur compounds to form a sludge, and separating the sludge from the hydrocarbon.

6. A process as claimed in claim 5 wherein the crude

hydrocarbon is contacted with about 0.1 to 2% by weight of alpha-sodium-sodium acetate.

7. A process as claimed in claim 5 wherein the crude hydrocarbon is contacted with alpha-sodium-sodium acetate in the presence of an alcohol in the amount of 0.01 to 5% by weight as an activator.
